Des. 204,803
Patented May 17, 1966

204,803

CONCRETE PATIO FORM

Michael M. Leeth, 1221 Kamala, Oxnard, Calif.

Filed May 5, 1965, Ser. No. 85,118

Term of patent 3½ years

(Cl. D51—1)

FIG.1.

FIG.2.

FIG.3.

FIG.4.

FIGURE 1 is a perspective view of a concrete patio form showing my new design;

FIGURE 2 is a top plan view thereof;

FIGURE 3 is an elevational end view thereof; and,
FIGURE 4 is an elevational side view thereof.

I claim:

The ornamental design for a concrete patio form, substantially as shown.
